UNITED STATES PATENT OFFICE.

JOHN COBLEY UHLEIN, OF WATERTOWN, NEW YORK.

NON-REFILLABLE BOTTLE.

1,124,977.

Specification of Letters Patent.

Patented Jan. 12, 1915.

Application filed July 14, 1913. Serial No. 778,970.

To all whom it may concern:

Be it known that I, JOHN C. UHLEIN, a citizen of the United States, residing at Watertown, in the county of Jefferson and State 5 of New York, have invented certain new and useful Improvements in Non-Refillable Bottles; and I do hereby declare the following to be a full, clear, and exact description of the invention, such as will enable others skilled in the art to which it 10 pertains to make and use the same, reference being had to the accompanying drawings, and to the letters and figures of reference marked thereon, which form a part of this specification.

This invention relates to new and useful improvements in non-refillable bottles and the object in view is to produce a simple and efficient device of this nature so arranged 20 that, in the event of any attempt being made to refill the bottle, whether the same is located in a vertical, inclined or horizontal position, means is provided for causing the valve to seat against passage of any fluid 25 into the bottle.

My invention comprises various details of construction and combinations and arrangements of parts which will be herein-after fully described, shown in the accompanying drawings and then specifically defined in the appended claim.

I illustrate my invention in the accompanying drawings, in which:-

Figure 1 is a central vertical sectional view through the neck of a bottle and valve mechanism contained therein. Fig. 2 is a similar section showing the bottle tilted and the valve automatically seated. Fig. 3 is a detail perspective view of a shell contained within the upper portion of the neck. Fig. 4 is a detail perspective of a member having a recess with conical wall. Fig. 5 is a detail perspective view of the valve, and Fig. 6 is a detail perspective view of the shell containing the valve seat and guide ribs to the valve.

Reference now being had to the details of the drawings by letter, A designates the neck of a bottle, the inner wall of which 50 tapers slightly as at A' and B is a shell, the outer surface of which tapers to correspond with the tapering surface of the neck against which it contacts and by which it is supported. Said shell has a central opening 55 D, the upper marginal edge of which is slightly beveled as at E, forming a valve

seat, and radially and longitudinally disposed ribs F project from the inner surface of the chambered portion F' of said shell and which serve as guides for the valve H. 60 The upper portion of the inner surface of said shell flares outwardly as at I and its upper end is flat, as shown at K. Said valve, it will be noted, is formed on the arc of a sphere and is adapted to contact with 65 the beveled valve seat in whatever position the valve may be held within the neck when in contact with said seat and is provided with a shank portion H', the end of which is convexed as at N.

A member, designated by letter O which is cylindrical in outline, is provided with ribs O' projecting from the circumference thereof, the lower ends O² of which project below the lower end of said member and are 70 adapted to rest upon the flat top K of the shell B, allowing a slight space to intervene between the latter and said member through which liquid may be allowed to flow as it is dispensed from the bottle. The under surface of the member O is chambered and has a conical wall Q which, at its upper end, terminates in an aperture R leading through the top of said member and provided for the purpose of preventing any vacuum 85 which might otherwise form in the upper portion of the chamber Q' and which would have a tendency to hold the valve from moving to its seat to prevent the refilling of the bottle.

A double shell T, provided with passageway T' between the same and with its lower end T² flaring, is inserted within the neck with the inner flaring end resting upon the upper ends of the ribs O' upon the member 90 O, thus providing means for allowing the liquid to pass through intermediate the inner flaring end and the member O to allow liquid to flow from the bottle. The bottom T³ of the inner shell portion, as shown in 100 Fig. 2 of the drawings, is closed and which will prevent the possibility of a wire being passed therethrough in the event of any attempt being made to tamper with the valve to hold the same from unseating.

Upon reference to Fig. 1 of the drawings, the passageways through which liquid may pass out of the bottle, when the valve is unseated, is designated by arrows and in Fig. 2 the valve is shown as having been automatically closed by the tilting of the neck to substantially a horizontal position.

In operation, when it is desired to dispense liquid from the bottle, it may be done by merely tilting the bottle to allow the valve to fall from its seat, the liquid taking 5 the course designated in Fig. 1 by arrows. In the event of it being attempted to refill the bottle while the same is in upright position, the valve would, of course, close by gravity and, in the event of any attempt 10 being made to refill the bottle while turned down toward a horizontal position, it will be noted that the convexed end N of the valve stem, being in contact with the sloping surface of the chamber Q', will slide 15 down said surface and cause the spherical-shaped end of the valve to seat, the valve being guided in its movements by the projections or ribs upon the inner surface of the shell B as will be readily understood. 20 This action of the valve by gravity is so sensitive and positive that the slightest attempt to turn the bottle to a horizontal position will cause the valve to quickly slide to its seat, rendering it impossible to pour 25 or force any liquid into the bottle and any attempt to refill the bottle in the event of the latter being inverted would be naturally

prevented by the trapping of air within the bottle.

What I claim to be new is:—

A non-refillable bottle, a cup fitted therein and provided with an opening in its bottom, the inner wall of said cup flaring near its upper end, a member having a series of circumferential ribs which extend below the 35 lower end thereof and resting upon said cup, the under surface of said member having a conical-shaped recess formed therein and terminating at its apex in an aperture leading through the member, a valve with a 40 convexed surface and having a shank portion terminating in a convexed end adapted to have a sliding contact with the conical wall of said recess as the bottle, after having been 45 inverted to dispense liquid, is turned toward a horizontal position to cause the valve to move by gravity to its seat, as set forth.

In testimony whereof I hereunto affix my signature in the presence of two witnesses.

JOHN COPLEY UHLEIN.
